US00D542291S

(12) **United States Design Patent** (10) Patent No.: **US D542,291 S**
(45) Date of Patent: **** May 8, 2007**

(54) **BIOMETRIC READER**

(75) Inventors: **Steven Kang**, Jericho, NY (US); **Mark Basile**, Jericho, NY (US)

(73) Assignee: **bioMETRX, Inc.**, Jericho, NY (US)

(**) Term: **14 Years**

(21) Appl. No.: **29/252,518**

(22) Filed: **Jan. 24, 2006**

(51) **LOC (8) Cl.** 14-02

(52) **U.S. Cl.** **D14/384**

(58) **Field of Classification Search** D14/383-386,
D14/345; 356/71; 235/380, 382.5; 355/64,
355/65, 75, 81; 283/68-70; 382/124-126,
382/116

See application file for complete search history.

(57) **CLAIM**

The ornamental design for a biometric reader, as shown and described.

DESCRIPTION

FIG. 1 is a perspective front-side view of the biometric device in an open position;

FIG. 2 is a perspective front-side view of the biometric device in a closed position;

FIG. 3 is a front view of the device in an open position;

FIG. 4 is a right-side view of the device in an open position based upon the view in FIG. 3;

FIG. 5 is a back view of the device in an open position;

FIG. 6 is a left-side view of the device in an open position based upon the view in FIG. 3;

FIG. 7 is a top view of the device based upon FIG. 3; and,

FIG. 8 is a bottom view of the device based upon FIG. 3.

1 Claim, 7 Drawing Sheets
